UNITED STATES PATENT OFFICE.

BUDD BRONSON, OF LAKewood, OHIO, ASSIGNOR TO THE OHIO RUBBER COMPANY, OF CLEVELAND, OHIO, A CORPORATION OF OHIO.

HAIR-RUBBER PRODUCT.

Application filed December 5, 1925. Serial No. 73,383.

This invention relates to a hair rubber product and in its more specific aspect or when made into the form for which it has special utility, the invention relates to what I 5 term a hair rubber carpet.

The chief object of the invention is to provide a rubber product re-inforced and strengthened by animal hair and preferably a particular kind of animal hair so as to produce a product having great abrasive resistance and tensile strength.

A further object is to provide a distinct improvement over rubber mats, carpets and other floor covering such as those used in automobiles, by providing an article which, while approaching the appearance and general characteristics of hair tapestry carpet, has greater tensile strength and abrasive resistance.

20 The invention may be briefly summarized as consisting in a product having certain essential ingredients, the chief of which are rubber and animal hair and formed substantially as hereinafter described and set forth in the appended claims.

In the accompanying sheet of drawings Fig. 1 is a plan view of a hair rubber carpet embodying my invention and Fig. 2 is a cross sectional view of same.

30 In producing my improved product having the desirable properties or characteristics above described, I mix together rubber compound, containing a large percentage of pure gum, and stiff animal hair, preferably goat's hair and treat the ingredients, in fact, carry out the process in such a way that the hair is not broken down nor burned nor otherwise caused to lose its original form and characteristics.

40 The proportions of hair and pure gum will vary in accordance with the particular use for which the product is intended. In producing a hair rubber carpet suitable for covering automobile flooring, I have found that very good results are obtained by using about thirty-three and one-third percent by weight of pure gum, about the same amount of goat's hair, about sixteen and two-thirds percent of ground tire carcass, with the remainder made

up of small percentages of miscellaneous ingredients, which may include zinc oxide, cotton seed oil, lime, sulphur and a suitable accelerator.

By decreasing slightly the rubber content, and increasing the hair content, the appearance of hair tapestry carpet is approached to a slightly greater degree, but the tensile strength and abrasive resistance of the finished product is somewhat decreased.

45 In carrying out the process all the ingredients, with the exception of the goat's hair is milled or mixed for a certain number of minutes or until the compound is thoroughly mixed. Before removing the compound from the mixer the hair is fed rapidly between the rolls, the material removed from the mill, sheeted through a calender, blanked, and put up in rolls on cotton liners ready for vulcanization. The reason for mixing the hair for only a brief period of time is to prevent breaking down the hair fiber. I have found by experiment that if the hair is allowed to go through the entire mixing or milling process the fibers are broken down, 50 losing their identity in the finished product, 75 destroying the appearance of the material and reducing its abrasive resistance and tensile strength.

55 The hair is preferably dyed with aniline dyes before mixing with the rubber compound. I find that in this manner the desired coloring effects can be given to the finished article which are not destroyed by contact with air and sun light. On the other hand, I find that if dry pigments are placed 65 in the rubber mixture before vulcanization, the original and desired colors are lost to a large extent.

60 The product containing the ingredients and formed in the manner above explained 90 has the stiff animal hair in practically its original lengths interspersed throughout the mass.

65 To complete the product if to be used in forming hair rubber carpet, the calendered material is placed in a vulcanizing mold and with severe pressure the top face of the sheet 95 is molded to assume the form and appearance

of woven carpet, this being done in either steel or hard rubber molds and preferably the material is vulcanized in the molds. All this can be accomplished in standard steam 5 hydraulic presses.

- I prefer to re-inforce this hair rubber carpet with a backing of suitable woven material which may be burlap or other textile, which in some instances consists of carpet 10 woven especially for this purpose and without the yarn facing or usual top wearing surface. This woven backing is preferably frictioned on both sides with pure rubber and is vulcanized to the sheet of hair rubber carpet. This is preferably done by placing the 15 frictioned woven fabric in the mold of the vulcanizing press so that it is pressed firmly in contact with the hair rubber sheet at the same time that the latter is given on its top 20 face the molded tapestry carpet appearance, and the whole is vulcanized together while subjected to this pressure.

By this process there is produced a product 25 having the appearance of woven tapestry carpet, to some extent even to the nap, due to the ends of the goat's hair projecting through the top surface and for many purposes it is superior to tapestry carpets, rubber mats and other floor covering because the 30 abrasive resistance and tensile strength are greater. It is also waterproof and can be readily cleaned and retains its original appearance. Additionally it is sanitary; surface dirt may be removed easily and such dirt 35 or dust that would ordinarily become embedded in the weave of regular carpet or textile, remains on the surface and is easily brushed or washed off.

The product is very well adapted for floor 40 coverings in automobiles as it has the general appearance of tapestry carpet and can be used in place of carpet where carpet is now employed and is far superior to rubber mats which are objected to by many users due to 45 their cold appearance. Furthermore, my improved product is made in fairly large and long sheets and sections of suitable size and shape are blanked out of the sheet to fit the individual car design, and there is no necessity 50 for binding the edges and interior cut-outs, as is now done with carpet, thereby reducing the labor cost and equipment necessary for this work. Furthermore, since the 55 fabric backing, if the latter is employed, is thoroughly embedded in the hair rubber compound, it will not unravel. Finally it might be stated that the product is, of course, flexible, like tapestry carpet.

It is important in carrying out my invention 60 not only that the goat's hair be not broken down or pulverized, but that it be not burned at any stage of the process of producing the hair rubber product; therefore, care should be exercised that the calender 65 rolls do not become too hot and in fact, may

actually be cooled. Furthermore a fast accelerator is incorporated in the rubber mass for hastening the vulcanization since the material must be vulcanized at low temperature and for a short period of time to avoid burning or injuring the goat's hair. 70

Goat's hair has distinct advantages over 75 wool or other animal fibers, as I have found in actual practice that wool fiber and animal hair other than goat's hair break down more readily in the mills, thereby reducing the tensile strength and abrasive resistance and furthermore tend to more rapidly disintegrate the material. Furthermore the cheaper 80 grades of wool fibers, cotton shoddy, and other animal hair, such as cattle hair are usually so impregnated with dirt and other foreign matter as to be not controllable in producing a uniform product, and in addition 85 have the other disadvantages mentioned above.

In the drawing I have shown a section of 90 hair rubber carpet designated generally by the reference character 10 and composed of the body 10^a of hair and rubber and the backing 10^b of suitable woven fabric, virtually embedded in the hair rubber compound and vulcanized thereto.

While my improved hair rubber product 95 finds great utility in the production of hair rubber carpet for the reasons explained above and while I have described the process of working up the product into the form of hair rubber carpet, the product may be used in other forms and for other purposes, as for 100 example, in many instances where leather and special compounds are used for packing, washers and the like. In producing articles such as those just mentioned, the above described process utilized in forming the hair rubber carpet is carried out, though, of course, the molded fabric appearance is not given to the material, and the proportions of 105 the ingredients may be varied to suit the requirements.

I therefore do not desire to be confined to 110 the precise details described nor to the precise ingredients mentioned, except as to the essential ingredients, nor to any particular proportions of such ingredients, but aim in 115 my claims to cover all modifications which do not involve a departure from the spirit and scope of my invention.

Having described my invention, what I 120 claim is:

1. A rubber hair carpet provided with a tread surface having the appearance of woven fabric and composed of rubber having animal hair incorporated therein, portions of said hair being exposed at said tread surface and all vulcanized together. 125

2. Hair rubber carpet having a surface molded in simulation of woven carpet and composed of rubber compound having goat's hair incorporated and mixed therewith por- 130

tions of said hair being exposed at said surface and all vulcanized together.

3. An imitation carpet comprising rubber and hair of the stiffer type, the tread surface resembling the nap of a carpet due to the exposure of portions of said hair.

4. A hair rubber covering having a nap

surface resembling a woven carpet, and caused by having a portion of the hair exposed at said surface.

In testimony whereof, I hereunto affix my signature.

BUDD BRONSON.
